How to Use Agile's Patented Real-Time Nexus Study Program

Step 1: Gather your business's sales data from prior periods dating back to Jan. 1 2018 or the earliest you business began making sales into the U.S. (choose whichever date is more recent).

Step 2: Make sure your sales data includes only the following four fields formatted per the requirements below. A template to assist with formatting your sales data can be found here or by clicking the blue "Download Excel Template" button below. Your Excel file should be formatted with the following columns:

1. Invoice Number (Format as Text)
2. Date (Format as Date)
3. Account (Format Number)
4. Sales (Format as Text)

Step 3: In the upload box to the right, click the button to select your sales data in Excel format or drag and drop your Excel (.xlsx) file to upload your sales data.

Step 4: From the picklist of states to the right, select the states in which your business has a physical location. No physical nexus in any U.S. states? No problem! Then just proceed to step 5.

Note: If you do not make any selections, the states in which your business has physical nexus will not be included in the calculation of your business's nexus.

Step 5: Click the blue "Where Do I Have Nexus?" button to the right, below the list of the states.

Step 6: After your file is uploaded and validated, your report will be generated automatically and will be displayed in this browser window and then the output will be able to be exported or downloaded.

If you need a recap of the terms related to sales tax nexus used herein, please review this page.

Physical Nexus Locations

Please select the checkboxes to the left of the state(s) where you have any of the following:

- A physical location including an office, warehouse, building, or other place of business
- Inventory in a warehouse, even if the warehouse belongs to a 3rd party
- Employees, including those working from a home office
- Traveling salespeople (depending upon the number of days spent within a specific state)
- An independent contractor, but only if that contractor is working in a "sales or marketing capacity"
